UNITED STATES PATENT OFFICE.

IRA WALLACE SYLVESTER, OF PALMETTO, LOUISIANA.

PLOW.

SPECIFICATION forming part of Letters Patent No. 410,218, dated September 3, 1889.

Application filed April 23, 1889. Serial No. 308,289. (No model.)

To all whom it may concern:

Be it known that I, IRA WALLACE SYLVESTER, a citizen of the United States, residing at Palmetto, in the parish of St. Landry and State of Louisiana, have invented a new and useful Plow, of which the following is a specification.

This invention relates to that class of plows which are known as "double" or "middle" breakers; and it has for its object to provide the same with an adjustable vertical guide-plate adapted to extend into the ground in a line with the draft, and thereby steady the motion of the plow and lighten the draft.

15 The invention consists in the improved construction and arrangement of the said guide-plate, which will be hereinafter fully described, and particularly pointed out in the claim.

20 In the drawings, Figure 1 is a rear perspective view of a plow equipped with my improvement. Fig. 2 is a vertical transverse section. Fig. 3 is a horizontal sectional view taken on the line $x x$ of Fig. 2. Fig. 4 is a detail view in perspective of the parts constituting my invention.

The same letters refer to the same parts in all the figures.

25 A designates the beam, and B the standard, to which the double mold-board C is attached in any suitable manner.

D is the lister, which extends rearwardly from the foot of the standard, and which comprises two vertical plates E E, the front 35 ends of which may be formed integrally with or suitably connected to the foot of the standard.

F designates my improved guide-plate, which is arranged vertically between the lister-40 plates E E, between which the front end of said guide-plate is secured upon a pivotal bolt G. The rear end of the guide-plate F is secured by means of the heel-bolt H of the lister, which extends transversely through the plates E E and F, and to which the lower 45 end of the adjusting-brace I is also pivotally connected. The said adjusting-brace may be suitably connected with the beam of the plow; but it forms no part of my present invention.

50 The front or cutting edge of my improved adjustable guide-plate F may be either rounded or squared, as shown, respectively, in full and in dotted lines in the drawings.

hereto annexed, or it may be of any other 55 shape or configuration which experience shall prove to be preferable. To receive the pivotal bolt G and the heel-bolt H, the said plate F may be provided with transverse perforations J, or with slots K, extending to its upper 60 edge, in order to enable it to be readily removed by merely loosening the nuts on the said bolts. It is obvious that when the slots K are used the plate F may be easily adjusted vertically to any desired height. When 65 perforations J are used, I prefer to provide a series of such perforations for the passage of the heel-bolt H, in order to enable the rear or heel end of the said plate F to be conveniently adjusted.

70 From the foregoing description, taken in connection with the drawings hereto annexed, the operation and advantages of my invention will be readily understood by those skilled in the art to which it appertains. In 75 plows of the class to which my invention belongs the double mold-board and the absence of a landside render it difficult to guide the plow in a true line, and even when the ordinary lister is used it is always more or less 80 liable to swerve out of the line of the draft whenever exceptionally loose or hard portions are encountered in the soil, thus making a crooked furrow and greatly increasing the draft. By my invention the guide-plate extends downwardly from the lister and into 85 the soil, thereby steadyng the plow and preventing it from moving laterally in either direction.

Having thus described my invention, I claim 90 and desire to secure by Letters Patent—

In a double plow, the combination of the standard carrying the mold-board, the lister-95 plates secured to and extending rearwardly from the foot of said standard, the guide-plate having a cutting-edge and mounted adjustably between said lister-plates, and the adjusting-brace connecting the heel ends of the latter with the plow-beam, substantially as set forth.

100 In testimony that I claim the foregoing as my own I have hereto affixed my signature in presence of two witnesses.

IRA WALLACE SYLVESTER.
